SHIP SALVAGING APPARATUS AND METHOD
John J. Metzger, 519 S. 2nd St., Lindenhurst, N.Y.
Filed Nov. 26, 1957, Ser. No. 699,001
24 Claims. (Cl. 114—55)

This invention relates to a method of and an apparatus for salvaging large heavy objects such as ships lying below the water. The invention is particularly useful in, although it is not restricted to, the salvaging of large ships sunk in deep water at a depth beyond that at which divers may normally work for an extended period.

The invention has among its objects the provision of a novel method of salvaging objects sunk in the water.

Another object of the invention lies in the provision of a novel rig for water salvaging operations.

Yet another object of the invention resides in the provision of a novel method of and an apparatus for salvaging sunken objects substantially without or totally without the use of divers.

Still another object is the provision of a salvage rig for use in water salvaging operations which may be left without risk of damage and without the loss of any substantial amount of work in the event of a storm, and with which the salvage work may immediately be picked up again when the storm has subsided.

A further object of the invention resides in the provision of novel salvaging apparatus which is simple, economical to assemble and operate, and is rugged and trouble-free in operation.

A further object of the invention resides in the provision of salvaging apparatus wherein the various parts thereof are under complete control at all stages of the salvaging operation.

Still another object lies in the provision of salvaging apparatus which is efficient in breaking the object to be salvaged free from the mud or silt in which it may lie at the bottom of the water.

Still another object of the invention lies in the provision of an improved drawline and/or lifting cable or chain laying device.

Yet another object of the invention resides in the provision of an improved trench-forming device, in the specific apparatus shown such trench-forming device forming a part of the line or cable laying apparatus.

Other objects of the invention include the provision of a novel object-lifting device, a novel agitator means associated with the lifting device for aiding in the breaking of the object free from the mud or silt at the bottom of the water, and a novel remotely controllable, adjustable connecting mechanism between object-lifting devices and the lifting cables or chains which partially embrace the object to be lifted.

The above and further objects and novel features of the invention will more fully appear from the following description when the same is read in connection with the accompanying drawings. It is to be expressly understood, however, that the drawings are for the purpose of illustration only and are not intended as a definition of the limits of the invention.

In the drawings, wherein like reference characters refer to like parts throughout the several views,

FIG. 1 is a somewhat schematic view in plan of a sunken ship to be salvaged, the figure showing an intermediate position in the assembly of the salvaging rig;

FIG. 2 is a schematic view in perspective of the salvaging rig assembly in substantially completed condition, the distance from the surface of the water to the ship being greatly foreshortened for clarity of illustration;

FIG. 3 is a view in front elevation of the ship in righted and intermediate lifted position, additional or

2

alternative lifting buoys or pontoons which may be employed in the lifting process being shown in phantom lines, the illustration of the surface elements of the rig being simplified;

5 FIG. 4 is a view in side elevation with the ship lifted to lie on the surface of the water and with the hole in the hull of the ship temporarily patched;

FIG. 5 is a view in side elevation of a preferred form of drawline and/or lifting cable or chain-laying apparatus, such apparatus including a trench-forming tool;

10 FIG. 6 is a view in transverse section through the cable-laying apparatus of FIG. 5, the section being taken generally along the line 6—6 of FIG. 5;

FIG. 7 is an enlarged fragmentary view in longitudinal axial section through the cable-laying apparatus, the view being taken adjacent the transverse central portion of the apparatus;

15 FIG. 8 is an enlarged view in transverse section through one of the drawline storing and dispensing guide means disposed along the length of the trench-forming tool in the apparatus of FIGS. 5, 6, and 7;

FIG. 9 is a view in side elevation of a shoe or runner which forms a part of the cable or chain-laying means of the apparatus of FIGS. 5, 6, and 7;

20 FIG. 10 is a view in side elevation of a lifting device in the form of a pontoon or buoy, a portion of the pontoon intermediate the length thereof being broken away for economy of space, the wall of the pontoon being broken through at the water inlet and exhaust port, the 30 wall of the pontoon being additionally broken through at the passage therethrough receiving the lifting means such as a chain or cable, portions of the lifting chains and the agitating hoses disposed about the portions of the chains below the pontoons being fragmentarily shown; 35 and

FIG. 11 is a fragmentary view in side elevation of a lifting chain employed in the apparatus shown in FIG. 10, FIG. 11 showing the operating mechanism for the latching dogs on the chain, the dogs being shown in inactive position, that is, lying along the length of the chain.

40 The salvaging method and apparatus of the present invention are illustrated herein in connection with the raising of a large ocean liner sunk in deep water which, for purposes of illustration, is assumed to exceed in depth that at which divers may safely operate for extended periods. The present invention, as apparent from above, is designed to eliminate or substantially eliminate the use of divers, thereby markedly decreasing the hazards of 50 the salvaging operation.

Since the salvaging method and apparatus of the invention require no divers, at least after brief explorations of the object to be salvaged, the site of the salvaging operation can be left at almost any time by the surface vessels and personnel, after a minimum of operations necessary to secure the parts at the surface, since there is no problem of returning divers to the surface. Thus the rig may be quickly left, for example, when a storm of such force arises that it would be inadvisable 60 to continue salvaging operations at that time. The salvaging rig of the invention is of such character that the salvaging operations may quickly be resumed upon the return of the surface vessels and personnel to the site. At each stage of the salvaging operations, from the initial 65 placement of the main parts thereof to the lifting of the object to be salvaged, the various parts of the rig are under complete control at one or more stations at the surface of the water.

Proceeding now to a consideration of the drawings, there is shown in FIGS. 1 and 2 a large ship such as an ocean liner designated 10, lying on the bottom 11 of the ocean. The water above the ship is designated 12, and

the surface of the water by the character 14. The particular ship shown is one that has been sunk by an accident which resulted in the formation of a large hole 15 in a side thereof. For the purpose of description, it will be assumed that the bottom 11 lies at a comparatively great distance, on the order of 200 feet or more, below the surface, although it will be appreciated that the method and apparatus of the invention display great advantages in salvaging operations conducted at less depths.

In starting the salvaging operation, after the ship has been located, it is convenient to outline the ship by the series of small locating buoys connected by cables to magnetic grappling devices which attach themselves to the ship. For the purpose of simplification, such locating buoys and magnetic grappling devices are not shown in the drawings. It will be understood, however, that the ship may be outlined at the surface of the water in other manners. After the ship has been located and outlined, two laterally spaced main forward buoys 16 and two aft buoys 17 are now located at positions somewhat forwardly of and rearwardly of, respectively, the bow and stern of the ship. Buoys 16 and 17 may be secured in position by anchor lines, of which typical ones are indicated at 19. The respective buoys 16 and 17 are now connected by primary or longitudinal bridle cables 20, and the pairs of buoys 16 and 17 are connected as shown by transverse bridle cables 21 and 21'. The placing of the buoys 16 and 17 and the bridle cables, as described, may be conveniently carried out by small surface, tender vessels 22. The buoys 16, 17 and the longitudinal and transverse bridle cables not only serve to outline the site of the ship, but also function as the means at the surface of the water supporting the upper ends of the drawlines and/or ship-raising or lifting devices in the assembly of the salvaging rig.

A cable-laying apparatus or tool 24 is now sunk to the bottom of the ocean in a location somewhat forwardly of or rearwardly of, as the case may be, the bow or the stern of the ship. In the assembly illustrated in FIG. 1, the apparatus 24 has been sunk forwardly of the bow of the vessel. Apparatus 24, which will be described more fully in connection with FIGS. 5-9, inclusive, is in the form of a laterally symmetrical broad general V-shaped conduit which is of such breadth and depth as to embrace the lower part of the ship to be salvaged while having the branches or legs of the apparatus substantially spaced beneath and laterally of the ship. Apparatus 24 includes a tunnel or trench-forming device supplied with fluid, preferably water, under pressure; the trench-forming device is so constructed and arranged as to dredge a trench or passage beneath the vessel as the tool is moved longitudinally of the ship. Apparatus 24 is provided with one or more drawlines and/or lifting cable or chain-laying devices, so that the drawlines and/or lifting devices may be deposited or drawn in, respectively, beneath the ship and left at positions spaced longitudinally of the ship as the apparatus 24 travels therealong. For the purpose of simplicity of illustration, in FIGS. 1 and 2 of the drawing the elongated flexible means designated 31, which are shown in FIG. 1 as having been deposited by the apparatus 24, are assumed to be the actual lifting devices such as chains or cables. As will appear in connection with FIGS. 6 and 7, however, the flexible members deposited beneath the ship initially may be drawlines, the actual lifting devices being subsequently drawn into place around the ship.

The ends of the thus deposited drawlines and/or lifting devices 31 are secured to the portion of the salvaging rig which lies at the surface of the water. For this purpose there are preferably provided two secondary bridle members 30 and 30' which are secured between the traverse bridles 21, 21' and lie parallel to longitudinal bridles 20 but inwardly thereof, preferably somewhat laterally outwardly of the sides of the ship. The ends of

lifting members 31 are shown attached to the secondary bridle members at 32 and 32'. Although for the sake of simplicity only one lifting member 31 is shown at each location, and such locations are widely spaced, it will be apparent from FIG. 2 that a large number of lifting devices will be employed. Preferably the means attaching the lifting devices 31 to the secondary bridles are in the form of clamps, whereby the lifting devices may be taken up and re-clamped on the secondary bridles as the ship is gradually lifted. It will be understood that a substantial length of each end of lifting device 31 will be left extending beyond the secondary bridle, particularly on the "high" side of the ship, if the latter lies in tipped position.

In the embodiment shown, the apparatus 24 is symmetrically supplied with fluid, preferably water, under pressure, from both ends thereof. Flexible multiple supply hose devices 25 are connected between the respective ends of apparatus 24 and two tenders 22, as shown in FIG. 1. The tenders 22 move with the apparatus 24, so as to supply dredging fluid under pressure thereto and to serve as stations from which to draw in or deposit the drawlines and/or lifting devices beneath the ship 10. Apparatus 24 may be drawn progressively along and beneath the ship 10 by means of draw cables 26 which are attached at one end to terminal members 40 of the tool by means of suitable eye members 29 thereon, the draw cables running over suitable pulley devices 27 on the transverse bridle 21' and being drawn in by suitable winching means on the respective tenders 22. The tenders 22 will themselves be propelled as required to travel with apparatus 24. Thus, in the embodiment shown, the tenders 22, which carry pumping and valve devices (not shown) to supply multiple hoses 25, move progressively along the sides of the location of the ship 10, and by their winching devices, progressively pull in the draw cables 26 to cause apparatus 24 to move longitudinally beneath ship 10.

After the apparatus 24 has made a complete pass beneath the ship 10, and has laid drawlines and/or lifting devices at spaced intervals in such travel, the apparatus 24 and its traversing and fluid supply means may be removed from the site of the salvaging operations. If only drawlines were initially laid beneath the ship, the lifting devices, such as cables or chains, are now drawn into place and are secured at their ends to the surface rig in the manner shown in FIG. 2. Thereupon lifting pontoons 34 are attached to the lifting devices 31. In the arrangement shown, each of the pontoons 34 is adjustably secured to a set of three lifting devices 31. In mounting the particular pontoons shown, the upper ends of one run of lifting devices 31 are removed from their respective secondary bridle, the pontoon is installed on the lifting cables or chains, the pontoon is lowered along the lifting devices to the level desired, and the upper ends of such runs of the lifting devices are reattached to the secondary bridle. Consequently, such lifting devices remain available for the attachment of additional lifting pontoons or the removal of the pontoons already assembled thereon at any time. After a sufficient number of pontoons 34 have been initially mounted upon the lifting devices 31 at each side of ship 10, the pontoons are given sufficient buoyancy, by the blowing of a part of the water therefrom, to start the raising of the ship. If the ship has become embedded to a substantial extent in mud or silt on the bottom, the initial freeing of the ship from the bottom may be facilitated by agitating means, such as those shown in FIG. 10, disposed about the lower portion of the lifting devices beneath the ship. The number and location of the pontoons, and the manner and degree to which they are rendered buoyant during various stages of the ship-raising operation, depend upon the attitude and orientation of the ship in its sunken position, the extent and nature of the damages to the hull which caused its sinking, and the manner and the

distance through which the ship is to be towed after being raised.

In the present instance, by way of illustration, it will be assumed that it is desired to tow the raised ship in upright position and that a large part of the required buoyancy can be contributed by the hull of the ship after temporary repairs thereto. It will also be assumed that the sunken ship lies somewhat on its side, as shown. Accordingly, initially it is desired to produce more buoyancy in the pontoons on the low side of the ship than on the high side, so as to turn the ship into upright position. With the salvaging rig of the present invention, such operations can be carried out completely from the surface of the water.

Since lifting devices 31 will engage the ship substantially without slip, the degree to which the ship has been turned may accurately be gauged by the travel of the upper ends of lifting members 31 through the respective fastening means 32, 32' therefor, it being understood that the connections at 32, 32' are constantly taken up or let out as the position of the ship changes. After the ship has been turned into upright position, it may be lifted from the bottom by blowing the water to various degrees from the several pontoons so as to give the assembly of pontoons and ship the required buoyancy. During all these operations, the attitude or orientation of the ship both laterally and longitudinally is apparent at all times from the length of the various lifting devices and/or drawlines extending upwardly from connections 32, 32' at the secondary bridles.

It is assumed that the character of the damage to the ship has already been surveyed and that a temporary patch, which may be of the pneumatic type, to seal the opening 15 in the hull thereof has been made and is ready. As the ship nears the surface, the prepared patch, shown diagrammatically at 35 in FIG. 4, may be applied and sealed thereto. After this, buoyancy may be given the hull without any other operations, once the upper hatch covers of the hull have emerged from the water, merely by pumping the water from the hull. Should it be desired to utilize the added buoyancy of the hull which is potentially available while it is still an appreciable distance under water, this can be done, once the hull has been raised to a level at which divers may normally work for extended periods, by sealing as by welding the various hatch covers of the hull as well as applying the patch 35 when the ship is still under water at that level.

Turning now to the detailed construction of the cable-laying apparatus 24, the shape of such tool in side elevation is dictated by the shape of the cross section of the object to be raised. Thus, for the operation described, the tool is made generally symmetrical and of a broad V or a broad U-shape, having a depth sufficient to extend below the ship 10 at its greatest depth, and having a width at its upper end such that the branches or legs of the apparatus lie spaced from the object at its greatest width. The apparatus 24 will ordinarily have been assembled from a plurality of sections after a survey of the object to be raised. In addition to the above requirements, it is ordinarily preferable that the legs of the apparatus be of sufficient length so that their terminal members 40 lie above the upper level of the bottom 11 upon which the object lies.

The apparatus 24 as shown has two oppositely disposed bottom sections 36 joined at an apex 37, the upper ends of sections 36 having extensions 39 connected thereto. The above mentioned terminal fittings 40, at the upper end of each section 39, house joints (not shown) between the separate hose members 42 in the multiple flexible hoses 25 and tubes, to be described, supplying each of the sections of apparatus 24 with dredging fluid under pressure. The apparatus 24 is preferably subdivided into a number of compartments longitudinally thereof, each compartment having its separate dredging fluid supply. The tool shown is laterally symmetrical. The portion

thereof shown in FIG. 7 is typical of the construction of the compartments therealong. In the portion of the tool shown in FIG. 7, there are three subsections 44, 45, and 46, which are joined together in forming the tool. The joint between sections 44 and 45, which is typical of the joints, except that at the apex, in the tool, is formed by partitions 49 on the respective sections, the partitions having outwardly directed flanges 49', the flanges being sealed by gaskets and joining studs 50', as shown. Apex joint 37 may be formed, for example, by welding the abutting sections together. The side wall of each of the tool sections is provided with a plurality of jet-forming orifices 50, as shown in FIG. 7. Orifices 50 are preferably so disposed as to slant upwardly and outwardly so as to displace the mud and silt of the ocean bottom in that direction when fluid under pressure escapes from such orifices. The sections of the tool are divided by transversely extending partitions there being a partition 59 shown at the apex 37, two generally equally spaced intermediate partitions 56 and 57 in section 44 and a somewhat similar partition 55 in section 45. Either one or both of flanged members 49 also functions as a partition.

Each of the thus formed compartments 51, 53, 58, 52, 54, etc., in the tool is fed by its respective conduit extending longitudinally of the tool and connected at its outer end to an appropriate one of the hoses 42. The pipes 60, 61, 61', 62, etc., which serve the various compartments of the tool are arranged in the manner more clearly shown in FIG. 6. The central pipe 60, for example extends through all the transverse partitions and is welded thereto, terminating at its inner end within the sub-compartment 54. To aid in the distribution of fluid from conduit 60 throughout compartment 54, partition 59 is provided with a generally conical projection 64 confronting the orifice of the conduit.

Others of the pipes extend sequentially through and are sealed as by being welded to the various transverse partitions, each conduit terminating in the particular compartment which it is to serve. The various hoses 42, which are connected to the respective conduits of which those shown at 60-62, inclusive, are exemplary, are disposed in the flexible hoses 25, and lead to pumping apparatus on the respective tender 22. A separately operated valve, not shown, is associated with each such hose 45 on such tender, whereby the rate of flow of dredging fluid, such as water, under pressure to each sub-compartment of the dredging apparatus may be separately regulated.

During operation of the apparatus 24, its various compartments are supplied with fluid such as water in the required amounts. Such fluid, escaping from orifices 50, in combination with the weight of the tool, initially cause the tool to sink and/or bite its way into the ocean bottom in a position in alignment with the ship. Thereafter, the winching devices on the tenders 22 draw the tool slowly through the ocean bottom, the tenders keeping pace with apparatus 24. The amount of tension in the draw cables 26 required to move apparatus 24 is no more than that well within the capabilities of ordinary 60 winching apparatus, due to the cutting action exerted upon the ocean bottom by the jets issuing from orifices 50.

The tool 24, which is thus propelled through the ocean bottom beneath the object to be raised, makes possible the laying or drawing in, at various positions longitudinally of the ship, of drawlines and/or lifting cables and chains. In the embodiment shown, there are disposed a plurality, four shown, of tube-like guide members 66 which are disposed longitudinally along the upper edge of tool 24 in the manner shown in FIG. 6. In the embodiment shown, the flanges 49' are cut out on the top thereof, at a zone 65, to provide a space within which members 66 are received. The construction of members 66 and the nature of the bundles or packs of drawlines contained therein will be more readily appreciated from a consideration of FIG. 8.

As there shown, the tube 66 has a longitudinally extending slot 67 in the upper wall thereof, the slot being of a width but little exceeding the diameter of each of the drawlines 69 contained within tube 66. The drawlines are preferably initially held in a bundle or pack form, being secured together by a plastic material such as wax or tar. Thus the drawlines and their matrix of plastic material may be charged as a whole into the guide 66. The pack or bundle of drawlines will have been carefully assembled and oriented in guide 66 so that the drawlines may be removed from the member 66 through the slot 67 in a designated succession without any danger of entangling the drawlines with each other. Thus, after the tool 24 has reached a certain location beneath the ship, assuming that it is desired to deposit a drawline thereat, it is necessary only to exert tension upon the opposite ends of the drawline next to be withdrawn, so that the drawline passes radially outwardly through slot 67 and may be drawn upwardly partially to embrace the ship. Following this the opposite ends of the drawline are secured to the surface rig, as for example, to secondary bridles 30, 30'. Conveniently, the drawlines are of such length as to extend between tenders 22 when such drawlines are in devices 66, so that all drawline-laying operations may be conducted from the tenders.

The means for drawing in the lifting cables or chains are somewhat similarly disposed along the bottom of tool 24. As shown in FIG. 6, there are three tubular guide members 72 disposed longitudinally of the tool, the guide members fitting within aligned pockets 71 provided in the flanges 49 joining sections of the tool. Each of tubes 72 has a longitudinally extending slot 74 therein, there being a travelling runner or shoe 75 fitting within tube 72. Projecting in a radial plane from body 75 is a vane-like member 76 which provides a means of attachment of either a lifting chain 84 to be drawn in beneath the ship or a lifting cable 85 for the same purpose. The shoe 75 is provided with conical end portions 79 to which are attached eyes 80. Oppositely extending draw chains 81 are attached to rings 80 and extend along the tubes 72. Draw chains 81 are of sufficient length so that each has its outer end, provided with a ring 82, extending upwardly beyond the upper end of the respective tube 72 and to the respective tender 22. Thus the personnel on the two tender vessels 22 may readily cooperate to draw one of chains 81 while releasing the other, so that either a draw chain or a draw cable may be pulled into place beneath the ship 10.

The vessel is assumed in this example to be lifted by lifting chains 84. The construction of the pontoons 34, of the chains 84, and of their selectively operable means for attachment to pontoon 34 will be more readily understood upon consideration of FIGS. 10 and 11. The pontoon 34, as shown, is provided with the usual lashing rings 86 by which it may be manipulated. The pontoon is provided with a valve port 87' and with a selectively positionable valve member 89 so as to open or close the port. Port 87' is employed both as an inlet and an exhaust for admitting water into or exhausting it from the pontoon. The valve member 89 is under the control of a hydraulic or pneumatic motor 90, and is normally urged into valve-closed position by a coil tension spring 91. Motor 90 is provided with two ports 92 and 94, connected to sources of pressure to hoses, not shown, leading to the tender vessel. When port 92 is subjected to pressure and port 94 is opened to the atmosphere the valve port 87' is opened. When valve port 92 is connected to the exhaust and valve port 94 is connected to pressure, the port 87' will close. The pontoon is provided with an air inlet pipe 95 connected by a hose 96 to a source of air under pressure, as for instance to pumping apparatus on one of the tenders. By proper manipulation of the source of air pressure leading to hose 96 and of valve port 87', the pontoon 34 may be given the desired buoyancy at any time. Preferably port

87' is so located vertically of the pontoon that when the water in the pontoon is exhausted to the level of such port, the pontoon will have a predetermined buoyancy. In order to allow the further exhaustion of water from the pontoon, the latter is preferably provided at the bottom with a similar port and surface-controlled valve means therefor. Such port and valve means are designated by the same characters as those first described, but with an added prime.

10 The pontoon shown is designed to cooperate with three lifting chains 84. Three longitudinally spaced laterally central passages receiving the chain are disposed in sealed relation to the interior of the pontoon, the passages being formed by tubes extending centrally through the pontoon. The chains 84, in that portion thereof to which the pontoons are to be selectively coupled, are provided with selectively remotely operable dog devices 99 which, when in operative position, couple the chain to the pontoon and, when in inoperative position, allow the chain to pass freely through the passage through the pontoon.

15 Each dog device 99 has a latch member 100 which is connected at a central hole 102 to one end of a long link 101 of the chain 84. When latch member 100 extends across the length of the chain, it spans the end of the

20 25 25 passage through the pontoon and thus couples the pontoon to the chain. Preferably, although not necessarily, the surface of member 100 which is to contact the pontoon is provided with a central pilot portion 104 which stably positions it in the end of the passage through the pontoon.

30 35 35 The end of the next consecutive length of chain is attached to latch member 100 at a hole 105 which is laterally offset from the central hole 102. To one end of the latch member there is attached a latch-opening cable 106 and to the other end of the latch member there is attached a latch-closing cable 107. Such cables extend upwardly longitudinally of the chain to a control station at the respective tender. When the latch member is in its collapsed or inoperative position, it and the cables connected thereto extend freely downwardly through the respective chain-receiving passages through the pontoon.

40 45 45 The manner of operation of the dog devices will be readily understood by a comparison of FIGS. 10 and 11, in the latter of which the dog devices are shown in operative position. It will be apparent, that upon the pulling of cable 106, each of the latch devices there shown will be swung to a cross or operative position. The latch devices may be retracted from such operative position by pulling upon cable 107. The dog devices may selectively be operated to engage either the top or bottom of the pontoon, as required.

50 To aid in the initial freeing of the ship from the mud or silt in which it may have settled, the portions of lifting cables 85 which are to lie initially centrally of and beneath the ship are provided with sheathing in the form of 55 perforated hoses 109 as indicated in FIG. 10. There is no necessity for such hoses to extend upwardly into the passages through the pontoons, since the pontoons are not positioned at any time beneath the upper surface of the bottom upon which the ship rests. The hoses 109

60 65 65 may be connected to a suitable source of pressure, preferably water pressure, by a supply hose 111 connected thereto by a fitting 110. The hydraulic pressure may be derived from the same source, that on the tender, that supplies the dredging and cable-laying tool 24. At the beginning of the lifting operation, and simultaneous with the exertion on the ship of the first large lifting effort by the pontoons 34, the hoses 109 may be supplied with fluid, preferably water, under pressure. This has the tendency to break the vacuum between the ship and the mud or silt of the ocean bottom, thereby markedly decreasing the lifting effort which the pontoons would otherwise have to exert in the initial part of the lifting operation.

70 75 75 Although only a limited number of embodiments of the invention have been illustrated in the accompanying drawings and described in the foregoing specification, it

is to be expressly understood that various changes, such as in the relative dimensions of the parts, materials used, and the like, as well as the suggested manner of use of the apparatus of the invention, may be made therein without departing from the spirit and scope of the invention as will now be apparent to those skilled in the art.

What is claimed is:

1. The method of salvaging a large heavy object lying on the bottom of a body of water, comprising forming a trench in the bottom below the level of the object, the trench extending from one side of the object to the other, progressively extending the trench to cause its instantaneous position to travel substantially from one end of the object to the other, and during the formation and extension of the trench depositing elongated flexible object-embracing means extending from side to side of the object in the trench beneath the object at positions spaced longitudinally of the object.

2. The method as defined in claim 1, wherein the trench is formed and extended by a laterally extending bottom-cutting tool, and the elongated object-embracing means are deposited in the trench at the location of the cutting means.

3. The method as defined in claim 2, wherein the object-embracing means are adapted to lift the object.

4. The method as defined in claim 2, wherein the object-embracing means are drawlines, and comprising drawing elongated flexible object-lifting means beneath the object by the drawlines.

5. The method as defined in claim 1, wherein the material of which the bottom is composed is relatively soft, and comprising forming the trench by directing a plurality of streams of fluid under pressure outwardly against the material of the bottom from an elongated laterally disposed source of fluid under pressure, and causing the instantaneous position of the trench to travel longitudinally of the object by moving the source of fluid pressure and the streams of fluid longitudinally beneath the object.

6. The method of salvaging a large heavy object lying on the bottom of a body of water, comprising forming a trench in the bottom below the level of the object, the trench extending from one side of the object to the other, progressively extending the trench to cause its instantaneous position to travel substantially from one end of the object to the other, during the formation and extension of the trench depositing elongated flexible object-embracing means extending from side to side of the object in the trench beneath the object at positions spaced longitudinally of the object, positioning a longitudinally extending bridle line at the surface of the water along each side of the object, and securing the ends of the object-embracing means to the respective bridle lines.

7. The method as defined in claim 6, comprising positioning the longitudinal bridle lines by buoys anchored to the bottom.

8. The method as defined in claim 7, comprising positioning by buoys anchored to the bottom laterally extending bridle lines at the surface of the water beyond the ends of the object, the longitudinal bridle lines being secured to the lateral bridle lines.

9. The method as defined in claim 2, wherein the bottom-cutting tool is moved by cable means attached to the ends of the tool.

10. The method as defined in claim 9, wherein the cable means are guided at the respective sides of the object whereby the tool moves longitudinally of the object.

11. A rig for salvaging a large heavy object lying on the bottom of a body of water at a depth substantially beyond that at which divers may normally work for extended periods, comprising an elongated, trench-forming tool adapted to be introduced into the material of the bottom to lie beneath the object, the tool being adapted to form a trench extending beneath and laterally beyond the object and progressively to cause the instantaneous posi-

tion of the trench to travel longitudinally of the object upon movement of the tool longitudinally of the object, and means attached to the tool for depositing elongated flexible object-embracing means extending from side to side of the object in the trench beneath the object at positions spaced longitudinally of the object.

12. A salvage rig as defined in claim 11, comprising means for moving the tool longitudinally of the object.

13. A salvage rig as defined in claim 11, wherein the trench-forming tool comprises a conduit having a plurality of orifices in its sidewall, and means to supply the interior of the conduit with fluid under pressure whereby to form material-displacing jets at the orifices.

14. A salvage rig as defined in claim 13, wherein the orifices in the wall of the conduit generally on the respective sides of the midpoint of the length of the conduit are inclined radially outwardly and toward the respective outer ends of the conduit.

15. A salvage rig as defined in claim 13, wherein the conduit is provided with a plurality of serially arranged compartments, and comprising means separately to control the flow of fluid under pressure to the compartments.

16. A salvage rig as defined in claim 15, comprising a plurality of fluid supply pipes within the conduit, the pipes being connected to a source of fluid pressure at an outer end of the conduit, the pipes terminating at their inner ends in the respective compartments which they supply.

17. A rig for salvaging a large heavy object lying on the bottom of a body of water at a depth substantially beyond that at which divers may normally work for extended periods, comprising an elongated, trench-forming tool adapted to be introduced into the material of the bottom to lie beneath the object, the tool being adapted to form a trench extending beneath and laterally beyond the object and progressively to cause the instantaneous position of the trench to travel longitudinally of the object upon movement of the tool longitudinally of the object, and means for depositing elongated flexible object-embracing means extending from side to side of the object in the trench beneath the object at positions spaced longitudinally of the object, the tool having an elongated casing, and the means for depositing flexible object-embracing means in the trench comprising an elongated open-sided guide secured to and extending longitudinally of the casing.

18. A salvage rig as defined in claim 17, wherein the guide has a tube-like body and is located on the top of the casing, and there is a longitudinally extending narrow slot in the upper side of the body.

19. A salvage rig as defined in claim 18, comprising a plurality of relatively thin flexible drawlines disposed in parallel relationship in the tube-like body and adapted for sequential withdrawal therefrom generally radially outwardly through the slot.

20. In an underwater salvage rig, a holder and dispenser for a plurality of drawlines comprising an elongated tube-like body adapted to be disposed across an object to be engaged by one or more drawlines, said body having a longitudinally extending narrow slot in the wall thereof, and a plurality of relatively thin flexible drawlines disposed in parallel relationship in the tube-like body and adapted for sequential withdrawal therefrom generally radially outwardly through the slot.

21. A drawline holder and dispenser as defined in claim 20, comprising an adhesive material for temporarily holding the drawlines together as a group in the body, the adhesive material yielding to allow the sequential withdrawal of drawlines from the group.

22. A salvage rig as defined in claim 17, wherein the guide is located on the bottom of the casing, the open side of the guide is located adjacent the bottom thereof, and comprising a shoe-like runner adapted to be pulled along the guide therewithin, said runner having a fin adapted to project outwardly through the open side of

the guide, the fin having means adjacent its outer end for the attachment of an elongated flexible object-lifting means whereby the last named means may be drawn into object-embracing position by the runner.

23. A salvage rig as defined in claim 17, wherein the casing is in the form of a portion of a loop and is adapted to pass through the material of the bottom in a path spaced from the bottom and sides of the object. 5

24. A salvage rig as defined in claim 23, comprising means at both ends of the tool for supplying it with fluid under pressure, and means at the ends of the tool for drawing it beneath the object. 10
